Primary Examiner — Cynthia R Underwood(74) *Attorney, Agent, or Firm* — JCIPRNET**CLAIM**

The ornamental design for a hook for chair as shown and described.

DESCRIPTION

FIG. 1 is a perspective view of a hook for chair showing our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view thereof showing the hook for chair mounted on an unclaimed chair;

FIG. 10 is another perspective view thereof; and,

FIG. 11 is a perspective view thereof showing the hook in the usage status.
The even-dashed broken lines in FIG. 9-11 illustrate environment that forms no part of the claimed design.**1 Claim, 9 Drawing Sheets**(56)
